TYPEWRITER DESK

Linus G. Miller, Jasper, Ind., assignor to The
Jasper Desk Company, Jasper, Ind., a corpo-
ration of Indiana

Application May 20, 1942, Serial No. 443,712

14 Claims.

(Cl. 312—29)

This invention relates to typewriter desks. Its general object is to provide in a pedestal-type desk of substantially all-wood construction a typewriter supporting platform which with a typewriter mounted thereon may be moved easily and conveniently between a housed position within a pedestal of such desk and an extended, horizontal working position in front of such pedestal. A further object of the invention is to provide supporting mechanism for that platform which will hold the platform in its working position firmly and rigidly not only against vertical movement and vibration but also against horizontal movement and vibration.

A desk embodying my invention has the usual working top, and suitable supports therefor, including at least one pedestal. Within this pedestal there is mounted a supporting slide, on rails extending from the front to the rear of the desk. The slide is wide, and lies in an inclined position. It carries supporting brackets on which the typewriter platform is pivotally mounted for movement thereon between its horizontal working position and a depending carrying position in which the platform and the typewriter may be moved into the pedestal. The width and inclination of the slide, the position of the pivot axis, and the mounting position of the typewriter are correlated to give good typewriter support and to minimize the effort required to move the assembly between its working position and its housed position within the pedestal. The platform is additionally supported by co-operation of the load-carrying members at the front of the pedestal with an abutment and a mating abutment-engaging member spaced rearwardly from the pedestal front, which come into engagement when the platform is brought to its working position and which not only hold the platform horizontal, but also hold it against movement in a horizontal plane.

The accompanying drawing illustrates my invention. In such drawing: Fig. 1 is a front elevation showing my typewriter mechanism in the pedestal of a desk, with part of one corner post broken away to show underlying details of a retractable stop; Fig. 2 is a vertical section taken on the line 2—2 of Fig. 1; Fig. 3 is a horizontal section taken on the line 3—3 of Fig. 1; and Fig. 4 is a vertical section similar to that of Fig. 2 but with the typewriter platform shown in retracted position.

The desk shown has a working top 10 on a supporting pedestal including four corner posts or legs 11 with side panels 12 extending between

front and rear legs 11, a rear panel 13 between the two rear legs, a bottom panel 14, and a hinged door 15 for closing the front of the pedestal.

The outer wall 11—12 of the pedestal is fitted with a filler strip 16' lying against the inner surface of the panel 12 between the posts 11. Against such filler strip 16' is fastened a guide-rail 16 having a rabbet groove at its lower corner, to form with the filler strip 16 a downwardly open groove 17 adapted to receive the upper edge 18 of a slide 20. The lower edge 21 of that slide is received in a groove 22 of a horizontal lower rail 23 supported on the bottom wall 14 of the pedestal, and with the groove 22 extending parallel to the groove 17. The position of the rail 23 with respect to the rail 16 is such that the slide 20 lies in an inclined position, at an angle of the order of 70° with respect to the horizontal. To fix the limit of extension of the slide 22, it is provided with a suitable stop, such as the dowel pin 37 mounted just below the rail 16 in position to engage the rear surface of the front post 11 of the outer pedestal-wall.

The slide 22 carries a pair of brackets 25 which extend upwardly to approximately the level of the upper edge 18 of the slide 20 and are provided, near their upper free corners with pivot holes 26 disposed horizontally between the grooves 22 and 17, but desirably horizontally nearer to the groove 22 than to the groove 17. Those pivot holes 26 receive pivot pins 27 rigidly mounted on the under side of the typewriter platform 30. The platform 30 is thus pivotally supported on an axis parallel with slide movement, for pivotal movement between a horizontal working position (shown in full lines in Fig. 1) and a depending position (shown in broken lines in Fig. 1) in which it and its supported typewriter are wholly carried by the slide and may be moved therewith to a housed position within the pedestal. A bumper 38 is provided near the lower edge of the slide 20 to engage the lower surface of the platform when in this lowered position.

Just behind the front post 11 of the inner pedestal-wall there is a movable stop 31, which conveniently consists of a vertically extending, flexible strip of wood mounted on the lower rail 32 of the inner pedestal wall and extending upwardly, with its free upper end notched to provide a ledge 33 adapted to underlie and support the edge of the platform 30. Beneath such ledge 33, the stop 31 may be cut away to increase its flexibility, for it is sprung out of its normal position by engagement of the platform 30 to pass such platform as it is raised, and springs back to a sup-

porting position when such platform 28 reaches its raised position. A handle 34 connected to the stop 31 through the panel 12 provides a convenient means of retracting the stop 31 to permit the platform 28 to be lowered.

The typewriter platform 30 is a rigid board of suitable size to receive a typewriter, conveniently with a clear area when extended about 17 inches wide by from 17 to 22 inches long. Pedestal width is related to platform width so that when the platform is in raised position one edge will press against the face of the rail 16, and its opposite and free edge will lie adjacent the inner wall (to the right in Fig. 1) of the pedestal.

The total length of the platform 30, for which clear space must be provided within the pedestal, should be such that when extended about three-fifths of the total length of such platform is a clear area lying in front of the forward wall of the pedestal.

The brackets 25 on the slide 20 are disposed so that when the platform 30 is extended the rearward bracket 25 lies at the front wall of the pedestal and the forward bracket 25 is spaced forwardly about two-thirds of the distance to the forward edge in the platform 30. The slide 20 need not extend forwardly much beyond the forward bracket 25, but should extend rearwardly as far as the structure of the pedestal will permit.

At the rear edge of the clear typewriter-receiving area of the platform, in position to lie at the front of the pedestal when the platform is extended, there is an upstanding trim-strip 29, which serves to prevent papers, etc., from sliding out of reach within the pedestal, and also serves as a cross-brace for the platform near where it is supported by the stop 31. Behind such strip 29 and at or near the rear edge of the platform 30 there is an upstanding cross member 35. Its upper edge is beveled to form an upwardly presented, wide-angle wedge extending across substantially the entire width of the platform, but formed at its end near the pivoted side of the platform to avoid interference with pivotal movement. The member 35 moves with the platform, and when the platform is raised with the slide fully extended, the upper wedge-shaped edge is received within a mating groove in an abutment formed by a pair of strips 36 conveniently mounted on the under side of the desk top 10.

To move the typewriter and platform from the working position shown in Fig. 1 (in full lines) and in Figs. 2 and 3 to the housed position shown in Fig. 4, the stop 31 is retracted by means of the handle 34, and the platform 30 is lowered to the position against the bumper 38, as shown in dotted lines in Fig. 1, where it is wholly supported by the slide. The slide 20 may then be moved rearwardly to carry the platform and its typewriter into the pedestal, as shown in Fig. 4. To return the typewriter to working position, the slide 20 and its supported platform 30 are pulled forward until the stop 31 engages its co-operating post 11. The lower edge of the platform is then lifted until it is supportingly engaged by the stop 31, which movement will also bring the cross member 35 into mating engagement with the groove between the strips 36.

When the typewriter platform 30 is in its extended position, as shown in Figs. 1 to 3, its free edge will be supported on the stop 31 and it will be supported by the slide 20, at the pivot points located directly beneath the heavy portion of a typewriter mounted in the usual way, as shown in dotted lines in Fig. 1. For this support, the

slide 20 will be held firmly in its rail grooves by engagement of the pivot-side edge of the platform with the face of the rail 16, for such engagement, made as the platform is raised when the slide is in extended position, will pull the upper edge of the slide 20 against the side of the upper rail groove 17. Such engagement of the edge of the platform 20 with the face of the rail 16 will also serve to hold such platform against movement in the plane of its working position. It will be given important additional support, and its rigidity against both vertical and horizontal movement increased to the high point required for a typewriter support by other means with which the pivot 26-27 and stop 31 co-operate.

In this additional support, the stop 31 will operate as a load-carrying member at the free edge of the platform, and the rear pivot-pin 27 will act as a load-carrying member at a directly opposite point spaced inwardly from the other side of the platform, the load at this point being transmitted directly through the rear bracket 25, and slide 20, to an underlying point on the lower rail 23. Thus, at and near the front of the pedestal, the platform will have good load-carrying support, near its edges, at the point where it is cross-braced by the trim-strip 29. Behind this support, the rearwardly extending end of the platform will be firmly held down by engagement of the cross-member 35 with the abutment strips 36, so that the platform itself will be firmly supported as a cantilever beam. Moreover, the member 35 will be wedged between the abutment strips 36 over substantially the whole width of the platform, and will thereby prevent any movement of the platform 20 in the horizontal plane of its working position.

When the platform is in its lowered, carrying position, both it and its typewriter are wholly supported by the slide, in a depending inclined position calculated to permit clear entrance into the pedestal for housing. In such position, the center of gravity of the typewriter lies horizontally close to the lower slide, so that there is but a small side-thrust between the slide and its rails, which facilitates sliding movement.

The inclined slide and the location of the pivot axis as shown, makes for efficient use of the space provided by the pedestal, and adapts the structure for use in a pedestal of usual size.

I claim as my invention:

1. A typewriter mounting and housing structure, comprising a pedestal, a slide, a typewriter platform pivotally supported on said slide near the typewriter-rear side of said platform and having a horizontal working position, an upper guide rail for said slide adjacent the pivot-side edge of said platform in its working position, a lower guide-rail positioned a considerable distance beneath the working position of the platform and spaced inwardly from said pivot-side edge, the axis of said pivotal support being positioned inwardly from said edge to lie horizontally between the rail-engaging edges of said slide, a releasable support for the free edge of said platform, which permits it to be lowered from its working position to a depending carrying position wholly supported by the slide, a vertical face fixed with respect to said upper rail in position to be engaged by the pivot-side edge of said platform upon movement to its working position to exert a clamping side-thrust between said upper rail and said slide, a rearward extension on said platform, abutment-engaging means upwardly presented by said extension, and a fixed abutment adapted to

be engaged by and interfit with said abutment-engaging means.

2. A typewriter mounting and housing structure, comprising a pedestal, a slide, a typewriter platform pivotally supported on said slide near the typewriter-rear side of said platform and having a horizontal working position, an upper guide-rail for said slide adjacent the pivot-side edge of said platform in its working position, a lower guide-rail positioned a considerable distance beneath the working position of the platform, the axis of said pivotal support being positioned inwardly from said edge, a releasable support for the free edge of said platform, which permits it to be lowered from its working position to a depending carrying position wholly supported by the slide, a face fixed with respect to said upper rail in position to be engaged by the pivot-side edge of said platform upon movement to its working position to exert a clamping side-thrust between said upper rail and said slide, a rearward extension on said platform, abutment-engaging means upwardly presented by said extension, and a fixed abutment adapted to be engaged by said abutment-engaging means.

3. A typewriter mounting and housing structure, comprising a pedestal, a slide, a typewriter platform pivotally supported on said slide near the typewriter-rear side of said platform and having a horizontal working position, an upper guide-rail for said slide adjacent the pivot-side edge of said platform in its working position, a lower guide-rail positioned a considerable distance beneath the working position of the platform and spaced inwardly from said pivot-side edge, the axis of said pivotal support being positioned inwardly from said edge to lie horizontally between the rail-engaging edges of said slide, a releasable support for the free edge of said platform, which permits it to be lowered from its working position to a depending carrying position wholly supported by the slide, a vertical face fixed with respect to said upper rail in position to be engaged by the pivot-side edge of said platform upon movement to its working position to exert a clamping side-thrust between said upper rail and said slide.

4. A typewriter mounting and housing structure, comprising a pedestal, a slide, a typewriter platform pivotally supported on said slide near the typewriter-rear side of said platform and having a horizontal working position, an upper guide-rail for said slide adjacent the pivot-side edge of said platform in its working position, a lower guide-rail positioned a considerable distance beneath the working position of the platform, the axis of said pivotal support being positioned inwardly from said edge, a releasable support for the free edge of said platform, which permits it to be lowered from its working position to a depending carrying position wholly supported by the slide, a face fixed with respect to said upper rail in position to be engaged by the pivot-side edge of said platform upon movement to its working position to exert a clamping reaction between said upper rail and said slide.

5. A typewriter mounting and housing structure, comprising a pedestal, a slide, a typewriter platform pivotally supported on said slide near the typewriter-rear side of said platform and having a horizontal working position, an upper guide-rail for said slide adjacent the pivot-side edge of said platform in its working position, a lower guide-rail positioned a considerable distance beneath the working position of the plat-

form and spaced inwardly from said pivot-side edge, the axis of said pivotal support being positioned inwardly from said edge to lie horizontally between the rail-engaging edges of said slide, a releasable support for the free edge of said platform, which permits it to be lowered from its working position to a depending carrying position wholly supported by the slide in which position said platform is adapted to hold a typewriter disposed with its center of gravity horizontally close to said lower rail.

6. A typewriter mounting and housing structure, comprising a pedestal, a slide, a typewriter platform pivotally supported on said slide near the typewriter-rear side of said platform and having a horizontal working position, an upper guide-rail for said slide adjacent the pivot-side edge of said platform in its working position, a lower guide-rail positioned a considerable distance beneath the working position of the platform, the axis of said pivotal support being positioned inwardly from said edge, a releasable support for the free edge of said platform, which permits it to be lowered from its working position to a depending carrying position wholly supported by the slide, a face fixed with respect to said upper rail in position to be engaged by the pivot-side edge of said platform upon movement to its working position to exert a clamping side-thrust between said upper rail and said slide, a rearward extension on said platform, a cross-member at the rear of said member and having a wedge-shaped upper edge, and means forming a mating groove positioned to receive said wedge-shaped upper edge when said platform is in working position.

7. A typewriter mounting and housing structure, comprising a pedestal, a slide, means on which said slide is mounted for movement into and out of said pedestal, a typewriter platform pivotally supported on said slide on an axis generally parallel with slide-movement and near one upper corner of said pedestal, whereby when said slide is extended said platform may be moved between a horizontal working position and a depending position in which it may be carried inside the pedestal by movement of said slide, said platform being of a length to extend in its working position rearwardly a substantial distance into said pedestal, means for supporting said platform in its working position, including a retractable stop adjacent the front of said pedestal and providing an underlying support for the free side-edge of said platform, a cross member extending along the rear edge of said platform and having an upper edge which is beveled to form a wide-angle wedge, and means carried by said pedestal and forming a groove to receive said wedge in mating relationship, to position said platform in the plane of its working position.

8. A typewriter supporting structure, comprising a slide and supporting rails therefor, a typewriter platform pivotally mounted on said slide on an axis parallel to, and spaced inwardly from one side-edge of the platform whereby said platform may be moved between a depending position to be carried by said slide and a horizontal working position, releasable means for supporting the free side edge of said platform in working position, said structure including a fixed abutment generally parallel to said pivot axis and a fixed overlying abutment, both adapted to be brought into steadyng relationship with said platform when it is raised to its working position, said overlying abutment being positioned

to hold said platform downwardly at points a substantial distance rearwardly along the platform from said pivot support and said releasable support whereby to provide a cantilever support for said platform when in working position.

9. A typewriter supporting structure, comprising a slide and supporting rails therefor, a typewriter platform pivotally mounted on said slide on an axis parallel to, and spaced inwardly from one side-edge of the platform whereby said platform may be moved between a depending position to be carried by said slide and a horizontal working position, releasable means for supporting the free side edge of said platform in working position, and an overlying abutment positioned to be engaged when said platform is raised to working position to hold said platform downwardly at points a substantial distance rearwardly along the platform from said pivot support and said releasable support whereby to provide a cantilever support for said platform when in working position.

10. A structure as defined in claim 9, in which said overlying abutment and the platform part which it engages interfit to position the platform in the plane of its working position.

11. A typewriter carrier, comprising a pair of guide-rails, a slide mounted in said rails, said slide being wide and said rails being widely spaced vertically and spaced horizontally to position said slide in an inclined position, a typewriter platform pivoted to said slide on an axis parallel with slide-movement, said platform being movable through less than 90° between a horizontal working position and a depending position in which it is adapted to be carried by said slide in its movement, said pivot axis being positioned above and between the rail engaging edges of said slide.

12. A typewriter mounting and housing structure, comprising a pedestal, a wide slide, a typewriter platform pivotally mounted on said slide on an axis spaced inwardly from one side-edge of said platform and generally parallel with slide movement, and guide-rails for said slide to dispose it in an inclined position with its upper edge adjacent the pivot-side of said platform, said structure including an abutment in position to be engaged by the pivot-side edge of the platform as it is pivoted to horizontal position, there being slight interference between said abutment and said edge which tends to wedge said platform in the direction of its free edge to carry said slide at its upper edge toward a vertical position, and releasable means for holding said platform in horizontal position.

13. In a typewriter support, a wide slide adapted to slide longitudinally and being inclined to present one face laterally and upwardly, supports on said face extending to a position above said slide, a typewriter platform pivoted to said supports in said position on a longitudinal axis spaced from one edge of said platform, said platform being adapted to pivot from a horizontal working position to a depending position, the lower edge of said slide being below the depending edge of said platform, and fixed guide rails slidably engaged by the edges of said slide.

14. In a typewriter support, a wide slide adapted to slide longitudinally and being inclined to present one face laterally and upwardly, supports on said face extending to a position above said slide, a typewriter platform pivoted to said supports in said position on a longitudinal axis spaced from one edge of said platform, and fixed guide rails slidably engaged by the edges of said slide.
